UNITED STATES PATENT OFFICE.

THEODORE R. FRATTALLONE, OF NEW YORK, N. Y.

WASHING ATTACHMENT FOR TUBS.

Application filed March 8, 1926. Serial No. 93,208.

The present application is a modification of the embodiment shown in my Patent No. 1,625,806 of April 19, 1927, for improvements in washing attachments for tubs.

5 The principal object of the present invention is to provide an air injector which is adapted to operate in association with any suitable source of air.

10 Another very important object of the invention is to provide an attachment of this nature which is exceedingly simple in its construction, in that it is capable of being quickly, expeditiously, and easily assembled and disassembled and may be manufactured 15 at a very low cost, and yet will prove thoroughly reliable and efficient in use.

With the above and numerous other objects in view as will appear as the description proceeds, the invention resides in certain 20 novel features of construction, and in the combination and arrangement of parts as will be hereinafter more fully described and claimed.

In the drawing:—

25 Figure 1 is a sectional view through a tub showing my improved attachment in sectional elevation, and

Fig. 2 is a top plan view thereof.

Referring to the drawing in detail, it will 30 be seen that 5 designates a tub which may be provided with the cover 6, and in the present instance, one wall of the tub is provided at its upper edge with a notch 7. This tub has been shown merely by way of 35 example, and may be in the nature of the ordinary household tub or of a much larger variety, such as would be used in laundries of the commercial type.

Referring in detail to the attachment, it 40 will be seen that 8 denotes a pipe which has a flattened portion 9 for reception in the notch 7 not to interfere with the closing of the cover 6. This pipe 8 terminates at its inner end in a depending extension 10, externally threaded for receiving the 45 internally threaded collar 11 of a vertically disposed pipe 12 that depends inwardly into the tub. The bottom end of the pipe 12 is also externally threaded as is indicated at 13 50 for receiving a T coupling 14. The pipe 8 is adapted to be connected in any suitable manner as indicated at 15 with a source of compressed air.

When the attachment is to be used with 55 a household tub, an ordinary vacuum cleaner may be used as a source of air.

However, in a commercial laundry, it would probably be preferable to use air compressors or the like.

A nozzle frame indicated generally by 60 the letter A is attached to the coupling 14, and extends over the bottom of the tub. This frame may be of any desirable shape and formation, but in the present instance, I have shown a form which has proved 65 practical. This form of the frame is rectangular including side perforated pipes 16, end perforated pipe 17, and a pair of end perforated pipes 18. The pipes 18 are threadedly engaged with the T coupling 70 14. Elbow couplings 19 connect the end pipes 18 and the end pipe 17 with the side pipes 16. The plane of the frame A is disposed at right angles to the pipe 12 and therefore is disposed horizontally. 75

It is thought that the construction, utility, and simplicity of this invention will now be clearly appreciated by those skilled in this art without a more detailed description thereof. The parts are very compactly arranged, and may be conveniently and easily assembled or disassembled as desired. Because of the nature of the material from which the device is constructed, it may be manufactured at a very low cost. The 80 nozzle frame is made up of standard parts, the pipes being perforated, and no particular skill is necessary in the assembling of the device.

The present embodiment of the invention 90 has been disclosed in detail, since in actual practice, it attains the features of advantage enumerated as desirable in the statement of the invention and the above description. It will be apparent, however, that numerous 95 changes in the details of construction, and in the combination and arrangement of parts may be resorted to if desired, without departing from the spirit or scope of the invention as hereinafter claimed, or sacrificing any of its advantages. 100

Having thus described my invention, what I claim as new is:—

An attachment of the class described including a pipe adapted to be rested on the 105 upper edge of a wash tub said pipe having one end thereof engageable with a source of air, a second pipe threadedly engaged with the other end of the first pipe and depending downwardly therefrom interiorly 110 of the tub, a T coupling threadedly engaged with the lower end of the second pipe, a

pair of perforated pipes threadedly engaged with the T coupling to extend at right angles from the second pipe and in alignment with each other, elbow couplings on the ends of the pair of perforated pipes, a second pair of perforated pipes threadedly engaged with the elbows, a second pair of elbows threadedly engaged with the second pair of perforated pipes, and a perforated

pipe engaged with the second pair of elbows, said perforated pipes and elbows forming a rectangular nozzle frame disposed in a plane perpendicularly to the second pipe, said first and second pipes being the sole supporting means for the frame in the tub.

In testimony whereof I affix my signature.
THEODORE R. FRATTALLONE.
